his Attorneys.

UNITED STATES PATENT OFFICE.

ROBERT BROWN, OF SPRINGFIELD, OHIO.

CUTTER AND CUTTER-GUARD FOR HARVESTERS AND MOWERS.

SPECIFICATION forming part of Letters Patent No. 314,103, dated March 17, 1885.

Application filed December 7, 1883. (No model.)

To all whom it may concern.

Be it known that I, ROBERT BROWN, a citizen of the United States, and a resident of Springfield, in the county of Clark and State 5 of Ohio, have invented certain new and useful Improvements in Cutters and Cutter-Guards for Harvesters and Mowers, of which the following is a specification.

The object of my invention is, first, to provide a readily-detachable guard-finger, and, second, to provide a readily-detachable ledger-plate, secured and held firmly in position by the attachment of the guard-finger to the cutter-bar, so that the finger or guard can be 15 readily detached for renewal and the shear or cutter plate readily removed for being ground or replaced with new cutters. In guard-fingers hitherto constructed there has been a difficulty in the removal or renewal of the 20 same, and the cutters or shear-blades are usually secured by screws countersunk in the face of the plate. These become worn and rusted and the screw slots or heads broken, rendering their removal difficult as well as tedious.

25 My invention is a marked improvement over the old methods, as it provides for the easy ready removal of each of the parts. At the same time they are secured and held in position more firmly than by the ordinary methods, 30 avoiding the use of screws and the piercing of holes through the cutters, all of which will be fully described, and then pointed out in the claims.

In the drawings, Figure 1 is a side sectional 35 elevation of my improvement on line $x-x$ of Fig. 2. Fig. 2 is a top plan view. Fig. 3 is a sectional elevation on line $x'-x'$, Fig. 2. Fig. 4 is a section on line $y-y$, Fig. 2. Fig. 5 is a rear elevation of the guard-finger detached 40 from the finger-bar. Fig. 6 is a modification showing a side elevation, partly in section, of the guard-finger adapted to be attached to an ordinary finger-bar. Fig. 7 is a top plan view of the same. Fig. 8 is a rear sectional elevation on line $z-z$, Fig. 6. Fig. 9 is a detail view of a modification.

A represents the supporting finger-bar of the ordinary harvester; B, the guard-finger, and C a flange cast on and with the guard-finger B. The flange C is provided with a hook, c , which passes down behind the finger-bar A, and forms a groove between it and the

vertical flange C, for bracing it upon the finger-bar A.

D D represent through-bolts for rigidly securing the parts B C to the bar A.

The contour of the flange-plate C as shown in Fig. 5 is the preferred form.

The projections d form shoulders which bear against the shank of the bolts D, the heads 6c of which engage over the flanges C of two adjacent guards, holding the plate secure against lateral movement, and these shoulders, in conjunction with the bolts D and hook c , effectually prevent vertical movement of the C, guard-fingers. This form of constructing the guard-plate C has the advantage of allowing the guard-finger to be removed by the removal of one bolt only. A modification of this form of attachment might be made by having the 70 plate C made large enough to be pierced with holes for the bolts D, as shown in Fig. 9; but such construction would require the removal of two bolts in order to take off the guard-finger, but if so constructed it would still be a 75 feature of my invention.

E represents the cutter-bar and e the cutters, riveted thereto in the usual manner.

F represents the open slot in the guard-finger of the ordinary construction, except the 80 forward part is beveled or slotted out, as shown by dotted lines $b b'$ in Fig. 2.

G represents the ledger-plates, secured to the guard-fingers B.

g represents a slot or beveled orifice pierced 85 through the flange-plates C, the top portion of which is made of the contour to fit and receive the ledger-plates G, which are inserted through the rear of flange C, and the forward portion of each ledger-plate G is made to fit 90 into the recess indicated by dotted lines $b b'$. (Shown in Fig. 2.) Instead of these inclined slots, the finger might be gained and the ledger-plate G tenoned to fit the gain at the forward end; or any other form of recess may be 95 employed to prevent the lateral movement of the forward end of ledger-plate G in the finger B.

a represents a projection of the guard-finger B, resting upon the ledger-plate G, so as to 100 prevent movement, and forming the top of the recess.

In order to allow the surfaces of the guard-fingers upon which the ledger-plates G rest to

be more easily fitted, I core out two centers so as to form two ribs or ledges on the exterior or sides of the guard-fingers B, as shown at O, Fig. 4. By this mode of constructing the guard-fingers B the ledger-plates G are readily inserted and removed through the orifice *g* from the rear side of flange C, and yet the ledger-plates G are firmly held in their position against vertical, lateral, or forward movement, and they are securely held in position when the guard-finger B is rigidly secured to the finger-bar A, which rests against the rear end of the ledger-plates G.

I prefer to make the rear edge of the flange C with ribbed surfaces, as shown by letters *i n t*, as they are more easily fitted or trued off to bear equally against the finger-bar A.

s represents a downward extension opening through flange C, or is a prolongation of the coring out of the center, as shown at O, Fig. 4. It serves to allow the finger to be inserted a little distance to take hold of the ledger-plate G for inserting and removing the same.

Fig. 6 represents a modified construction of the detachable guard-finger B for securing it to the ordinary finger-bar, so as to utilize the detachable ledger-plates G, which are inserted in the guard-finger B, which is constructed in the same manner as shown in Figs. 1, 2, 3, 4, 30 and 5, except a portion of the flange C and the hook *c* are omitted and a horizontally-extended flange, H, is projected upon the rear end of guard-finger B, for securing it to the finger-bar I.

The guard-fingers B are further modified so as to conform to the shape of the ordinary fingers of the finger-bar; but the mode of coring out and forming the grooves for the ledger-plates G to rest in is substantially the same as those shown in the other figures of the drawings. These ledger-plates G are inserted and removed and held in position in

the same manner with the mower-finger as with the harvester-finger, and have the same advantage of removal and renewal. The rear ends of the ledger-plates G are held in vertical positions by means of a flange, C, as shown in Fig. 6.

Various modifications may be made in the shape and contour of these fingers and attached parts without affecting the principal features of my invention, one of which is the use of a detachable ledger-plate, G, which is held in position without being pierced with screw-holes.

What I claim is—

1. The detachable guard-finger B C, having the slot *g*, and adapted to receive and hold the ledger-plates G, substantially as described.

2. The detachable guard-finger B C, having the slot *g* in the rear and the slot or recess *b* in the front for receiving the ledger-plate G, substantially as described.

3. The detachable guard-finger B C, having the slot *g*, in combination with the ledger-plate G and finger-bar, substantially as described.

4. In combination with the detachable guard-finger B C, the flange C thereof provided with the hook *c* and bolt-shoulders *d*, adapted to be secured to the finger-bar A by bolts D, substantially as described.

5. The detachable guard-finger B C, the flange C thereof having hook *c*, adapted to fit over and be secured to the bar by the heads 75 of bolts D engaging over the flanges of two adjacent guards, substantially as described.

In testimony whereof I have hereunto set my hand.

ROBERT BROWN.
